(57) **CLAIM**

The ornamental design for a graduated catheter, as shown and described.

DESCRIPTION

This design application is related to U.S. Design patent application Ser. No. 29/499,859 filed on Aug. 19, 2014.

FIG. 1 is a perspective view of a graduated catheter.

FIG. 2 is a right side view of the graduated catheter.

FIG. 3 is a top view of the graduated catheter.

FIG. 4 is a bottom view of the graduated catheter.

FIG. 5 is a left side view of the graduated catheter.

FIG. 6 is a front view of the graduated catheter; and,

FIG. 7 is a rear view of the graduated catheter.

The catheter is shown with a symbolic break in its length in FIGS. 1-5. The appearance of any portion of the article between the break lines forms no part of the claimed design.

1 Claim, 3 Drawing Sheets
